(57) **CLAIM**

The ornamental design for a flat bottom vee ice skate blade, as shown and described.

DESCRIPTION

FIG. 1 is a perspective view of a first embodiment of a flat bottom vee ice skate blade.

FIG. 2 is an enlarged front side view of the ice skate blade of FIG. 1.

FIG. 3 is an enlarged rear side view of the ice skate blade of FIG. 1.

FIG. 4 is a reduced top view of the ice skate blade of FIG. 1.

FIG. 5 is a reduced bottom view of the ice skate blade of FIG. 1.

FIG. 6 is a right side view of the ice skate blade of FIG. 1.

FIG. 7 is a left side view of the ice skate blade of FIG. 1.

FIG. 8 is a greatly enlarged close-up of the front side of FIG. 2.

FIG. 9 is a cross-sectional view of the ice skate blade taken from line 9-9 of FIG. 2.

FIG. 10 is a perspective view of a second embodiment of a flat bottom vee ice skate blade.

FIG. 11 is an enlarged front side view of the ice skate blade of FIG. 10.

FIG. 12 is an enlarged rear side view of the ice skate blade of FIG. 10. FIG. 13 is a reduced top view of the ice skate blade of FIG. 10.

FIG. 14 is a reduced bottom view of the ice skate blade of FIG. 10.

FIG. 15 is a right side view of the ice skate blade of FIG. 10. FIG. 16 is a left side view of the ice skate blade of FIG. 10; and,

FIG. 17 is a greatly enlarged close-up of the front side view of FIG. 11.

The broken line showing of portions of an ice skate is included for the purpose of illustrating environmental structure and forms no part of the claimed design.

1 Claim, 13 Drawing Sheets
